tion of Pennsylvania

Application December 27, 1948, Serial No. 67,393

9 Claims. (Cl. 246—161)

1

My invention relates to railway traffic controlling apparatus and particularly to apparatus for interlocking and coordinating the operation of an outlying track switch with a signal controlling traffic movement over the switch.

In railway signaling and traffic controlling systems, outlying track switches, that is, switches outside of yards and interlocking plants, are commonly protected against operation by unauthorized persons by means of padlocks which may be opened by keys carried by certain selected railway personnel. It is sometimes necessary or desirable to supplement the protection obtained from the use of a padlock by adding another switch lock which may be controlled manually from a remote point or automatically in accordance with traffic conditions, etc. For example, when a switch is associated with a main track provided with an automatic signal system, a common expedient is to provide a time control for the switch lock. The switch lock is then provided with signal controlling contacts which are operable at any time after removal of the padlock to set the signals to stop. The timing mechanism, which may be either electric or mechanical, is started at the same time the signals are set to stop, and releases the switch lock at the expiration of a predetermined time. This period of time is chosen long enough so that any train which has passed the signal nearest the switch will have time to proceed past the switch before the lock is released.

The setting of the signals to stop by such a lock may be accomplished either through the use of suitable line circuits controlled by the lock or, where track circuits are employed, the lock contacts may be used to shunt the track rails. In electrified territory, the track shunting contacts must be made large enough to take care of any flow of propulsion current which might take place because of a potential difference between the rails. In such cases, the size of the contacts required is so great that they cannot be placed within the casing of the usual electric lock. The problem of properly shunting the track rails under such conditions is further aggravated by the lack of space which is typical of the congested territory where most electric railroads are located. Those congested conditions require the mounting of as much equipment as possible between the track rail, with a consequent limitation of the maximum height of the equipment.

A system of the type described, for controlling an electric lock on an outlying switch, is shown and claimed in the copending application for

2

Letters Patent of the United States of Howard A. Thompson, Serial No. 749,833, filed May 22, 1947, now Patent Number 2,539,937, dated January 30, 1951, for Traffic Protection Apparatus.

5 An electric switch lock suitable for mounting between the rails of a railway track is described and claimed in the copending application for Letters Patent of the United States of Herbert L. Bone, George L. Temple and John W. Logan, Jr., Serial No. 721,028, filed January 9, 1947, now Patent Number 2,517,280, dated August 1, 1950, entitled Electric Locks.

An object of my invention is to provide improved apparatus for interlocking a signal controlling lever with an electric lock which cooperates with a switch controlling lever, of the type described in the copending Thompson application referred to above.

Another object is to provide improved means 20 for interlocking the manual operating lever of a heavy duty circuit controller with an electric lock which cooperates with an associated switch controlling lever.

Another object is to provide improved means 25 or interlocking the hand-throw lever of a circuit controller with the foot pedal of a switch lock.

A further object is to provide an improved 30 interlocking structure adapted for mounting between the rails of a railway track.

In carrying out the foregoing and other objects 35 of my invention, I utilize an electric switch lock of the type described in the Bone, Temple and Logan application previously referred to. In the installations described herein, this lock is mounted between the rails of a crossover track so as to lock the center throw lever associated with the crossover.

In one modification of my invention, I mount 40 a known type of heavy duty circuit controller outside the track rails and connect it through suitable linkage to a hand-throw lever mounted between the rails. I then provide an improved interlocking mechanism connecting the hand-throw lever of the circuit controller with the lever latch on the switch lock associated with the center throw lever. This interlocking mechanism 45 comprises an abutment connected to the lever latch of the switch lock so as to move concurrently with it, and a bolt arranged to move into and out of the path of the abutment and connected by a link to the hand-throw lever of the circuit controller.

In another modification of my invention, I 50 employ a heavy duty circuit controller of the type shown in the copending application for Letters

Patent of the United States of William R. Gracey, Jr., entitled Electric Circuit Controllers, Serial No. 67,264, filed December 27, 1948. This circuit controller is adapted for mounting between the track rails and is provided with a hand-throw for operating the controller contacts and another built-in hand-throw lever which is used, in the installation described herein, as the center throw lever of the crossover. A switch lock is provided to cooperate with this center throw lever, and a modified and more compact form of my improved interlocking mechanism connects the operating lever of the circuit controller with the lever latch of the switch lock.

I shall describe two forms of railway traffic controlling apparatus embodying my invention and shall then point out the novel features thereof in claims.

In the accompanying drawings, Fig. 1 is a diagrammatic view illustrating my invention as applied to a crossover track between two main line tracks, including a wiring diagram of the electric circuits and showing the principal mechanical elements diagrammatically. Fig. 2 is a track layout of the crossover shown in Fig. 1, illustrating the relative locations of the various items of equipment. Fig. 3 is a plan view illustrating the electric lock for the center throw lever, the hand-throw lever for the circuit controller, and the connecting interlocking mechanism, all of which are illustrated schematically in Figs. 1 and 2. Fig. 4 is an elevational view of the apparatus of Fig. 3, with certain parts shown in section and other parts broken away to permit better illustration of the essential features. Fig. 5 is a plan view of an electric circuit controller of the type shown schematically in Figs. 1 and 2 with the cover removed. Fig. 6 is a sectional view of the circuit controller of Fig. 5. Fig. 7 is a track layout similar to Fig. 2, illustrating a crossover track equipped with apparatus embodying my invention in a modified form. Fig. 8 is a plan view illustrating the center throw lever, the electric lock, the circuit controller, and the interlocking mechanism which are shown diagrammatically in Fig. 7. Fig. 9 is an elevational view of the apparatus of Fig. 8.

In each of the several views similar reference characters refer to corresponding parts.

Figs. 1 to 4

There is shown in these figures a stretch of railway comprising insulated sections 1T and 2T of two main tracks. A crossover track 3 extends from a switch 1 in the track section 1T to a switch 2 in the track section 2T.

Each of the track sections 1T and 2T is provided at its exit end with a track battery, such as 1TB and at its entrance end with a track relay, such as 1TR. Track relay 1TR controls over a front contact a signal 1S governing westbound traffic. Only a portion of the energizing circuit of the signal 1S is shown. The letters B and C at the opposite ends of this circuit portion represent the terminals of a local source of electrical energy such as a battery. Track relay 2TR similarly controls a signal 2S governing eastbound traffic.

The switches 1 and 2 are operable by manual switch machines 1W and 2W, respectively, of conventional construction. Each switch machine is provided with a hand-throw lever, such as 1V and a lock bar, such as 1L. The lock bars 1L and 2L of both switch machines are operated from the center of the crossover track by means of a center throw lever 4, the arrangement being

generally similar to that shown in Letters Patent of the United States No. 1,654,023, issued to C. C. Thorn, on December 27, 1927, for Switch Throwing and Locking Mechanism. The center throw lever 4 is movable between the normal position shown in the drawings, in which both the switch machines 1W and 2W are locked, and a reverse position in which the lock bars 1L and 2L are withdrawn so that the switch machines may be operated by their respective levers 1V and 2V.

An electric switch lock, generally indicated at 5, is provided for retaining the center throw lever 4 in its normal position. I prefer to use an electric switch lock of the type shown in the copending Bone, Temple and Logan application previously referred to. The various elements of the lock structure shown in Fig. 1 have their functional counterparts in the Bone et al. lock. The structure of the elements has been modified in Fig. 1 in order to simplify the diagrammatic drawing. This lock includes a lever latch 6 which obstructs the path of movement of the center throw lever 4 away from its normal position. A pedal 7 is connected to the lever latch 6 so that when the pedal is depressed, the lever latch is moved out of the path of the center throw lever 4. A locking member or segment 8 is connected to the pedal 7 and latch 6 for concurrent movement therewith. A locking dog 9 cooperates with the segment 8, and in the position shown in Fig. 1, the dog 9 prevents movement of segment 8 in a clockwise direction and thereby prevents release of the lever 4 by the lever latch 6.

The lock dog 9 is carried at the end of an armature 10, which is movable by energization of an electric lock winding 11 from the locking position shown to an unlocking position in which the dog 9 is free of the locking segment 8, so that the segment 8 and lever latch 6 are free to move upon depression of the pedal 7.

A cam 6a which moves concurrently with the latch 6 operates a follower on one arm of a bell crank lever 6b. The other arm of lever 6b overlies the locking dog 9. A spring 6c biases the lever 6b in a direction to hold the follower in engagement with the cam. The cam 6a is contoured so that if the locking dog 9 sticks in its unlocked position when the latch 6 moves to its latching position, then as one arm of lever 6b follows the cam, the other arm engages the locking dog, forcing the latter to its locking position. The contour of cam 6a is so related to the structure of locking segment 8 and latch 6 that when the pedal 7 is depressed, cam 6a can move far enough to carry lever 6b away from dog 9 before the latter arrests movement of the segment 8. Thus the lever 6b does not interfere with unlocking of dog 9. The latch 6 is constructed so that it holds the lever 4 in the normal position shown until after the segment 8 has passed the position where it may be stopped by dog 9. Hence if the segment 8 is stopped by dog 9, the lever 4 remains latched.

A hollow shaft 12 (Figs. 3 and 4) is rotatably mounted at one end on the housing of the switch lock 5 and has its other end journaled in the housing 13 of an interlock mechanism generally indicated at 14. The shaft 12 is provided with a torque arm 15 carrying a pin 15a extending parallel to the shaft 12 and through a suitable aperture in the pedal 7. In this manner, the shaft 12 is made to rotate concurrently with movement of the pedal 7.

Inside the housing 13 of the interlock mechanism 14, the shaft 12 carries a disc 16 provided

with an eccentric aperture 16a adapted to receive a bolt 17. The bolt 17 extends outwardly through and is guided by the housing 13, and is pivotally connected at its outer end to one end of a link 18. The other end of link 18 is pivotally connected to a hand-throw lever 19 mounted on a lever stand 20 and connected through suitable linkage (see Fig. 2) to a heavy duty circuit controller generally indicated at 21.

The circuit controller 21 is described in detail in connection with Figs. 5 and 6. Referring for the moment to Fig. 1, it may be seen that the controller 21 includes two sets of heavy duty contacts 22 and 23 and one set of light duty contacts 24. The heavy duty contacts 22 and 23 are made of sufficiently large capacity to shunt track circuits in electrified railways where the flow of propulsion current through such a shunt may be heavy. The contacts 22 are connected to shunt the track rails of section 1T and the contacts 23 are connected to shunt the track rails of section 2T.

The light duty contacts 24 are open when the parts are in the position shown in Fig. 1. The light duty contacts 24 control circuits including a stick relay SR and a time element relay TE, which in turn controls the energization of the electric lock winding 11. The stick relay SR is a repeater of the light duty contacts 24, and has a pickup circuit including the contacts 24 and a back contact of the time element relay TE. The latter contact checks that the time element relay is closing its back contact whenever a timing cycle is initiated, and thereby prevents the occurrence of a short timing cycle due to closure of contacts 24 when the contacts of relay TS are not in their normal position. Stick relay SR also has a stick circuit including its own front contact and the contacts 24, which is independent of the back contact of time element relay TE. The energizing circuit of time element relay TE includes a front contact of stick relay SR and the light duty contacts 24 of the circuit controller 21.

Operation—Fig. 1

When the parts are in the positions shown, the pedal 7 is doubly locked, once by bolt 17 and once by lock dog 9. If the hand-throw lever 19 of the circuit controller 21 is then moved to its reverse position, the bolt 17 is moved out of the aperture 16a in the interlocking disc 16. Also, the signals 1S and 2S are set to stop by the action of the heavy duty contacts 22 and 23 in shunting the track circuits. At the same time, the contact 24 is closed, thereby energizing stick relay SR which in turn closes its front contact to energize time element relay TE. Upon energization of stick relay SR, it closes its own stick circuit, so that relays SR and TE remain energized as long as contact 24 is closed. After the time for which the relay TE is set has expired, it closes its front contact, thereby completing an energizing circuit for electric lock winding 11. Then, as soon as pedal 7 is moved far enough to carry the end of lever 6b away from the lock dog 9, the winding 11 moves lock dog 9 away from the locking segment 8 and thereby releases the pedal 7, so that it may be further depressed to carry the lever latch 6 out of the path of the center throw lever 4. The center throw lever 4 may then be thrown to release the two switch machines 1W and 2W. The switches 1 and 2 may then be reversed so that the crossover track 3 can be used.

When it is desired to return the parts to their

normal position, the switches 1 and 2 must first be set normal by the use of their respective operating levers 1V and 2V. The levers 1V and 2V are then locked normal by returning the center throw lever 4 to its normal position. The pedal 7 may then be lifted to its normal position. After the pedal 7 is restored to its normal position, the hand-throw lever 19 of the circuit controller 21 may be restored to its normal position.

The pedal 7 is held down while the lever 4 is away from its normal position by means of a lever lock rod 4a (Figs. 1, 3 and 4), coacting with a lug 4b provided on the lever latch 6. During that time, the aperture 16a in disc 16 is out of registry with the bolt 17, so that restoration of the hand-throw lever 19 to its normal position before the pedal 7 reaches its normal position is prevented.

From the foregoing, it may be seen that my improved interlocking mechanism insures the proper sequence of movement of center throw lever 4 and circuit controller lever 19. When both levers are in their normal positions, the lever 19 must be reversed to set the signals at stop before the lever 4 can be reversed. When both levers are in their reverse positions, lever 4 must be restored to normal before lever 19 can be restored to normal so as to permit clearing of the signals.

Instead of providing a time control for the electromagnet 11, as described, other suitable control circuits may be used. For example, the electromagnet may be controlled manually from a remote location such as a dispatcher's office or interlocking tower, or it may be controlled automatically in accordance with traffic conditions, etc.

Figures 5 and 6

These figures illustrate the details of construction of the circuit controller generally indicated at 21 in Figs. 1 and 2. In Figs. 5 and 6 it may be seen that the heavy duty contacts 22 and 23 comprise a pair of movable knife blades 22a and 23a, which cooperates with stationary spring blade contacts 22b and 23b. The knife blades 22a and 23a are pivotally mounted at one end on electrically conductive brackets 22c and 23c. The free ends of the knife blades 22a and 23a are connected by an insulating yoke 25 to one arm of a bell crank lever 26. The other arm of lever 26 is pivotally connected to a link 27, whose opposite end is pivoted on a crank arm 28 adjustably fixed on an operating shaft 29 by means of a split clamp.

The light duty contacts 24 include a pair of contact fingers 24a and 24b which are self biased to engage an insulating drum 30 carried on the shaft 29. A conducting strip 24c is attached to the drum 30 at a position such that the contact fingers 24a and 24b will be electrically connected through the strip 24c when the heavy duty contacts 22 and 23 are closed.

The brackets 22c and 23c are attached by means of bolts to suitable cables 31 which extend outwardly through insulating parts of the casing. The spring blades 23b of the heavy duty contacts are similarly connected to conductors 34 which extend outside the casing.

Figures 7 to 9

There is shown in these figures a modified form of railway traffic controlling apparatus embodying my invention. In this arrangement, the lock bars 1L and 2L of the two switch machines 1W and 2W are connected through a suitable link-

age to a center throw lever 36 associated with a heavy duty circuit controller 37 of the type disclosed in the copending application of William R. Gracey, Jr., previously referred to.

The circuit controller 37 is provided with heavy duty and light duty contacts whose functions are the same as for the corresponding contacts in the circuit controller 21 of Figs. 1 to 6. The circuit controller 37 is attached to a mounting plate 38 bolted to the ties of the railway track. An electric lock 39 for the center throw lever 36 is also mounted on the plate 38. The electric lock 39 is provided with a latch 40 which holds the lever 36 down, and a pedal 41, by means of which the latch 40 may be released whenever the electric lock 39 is energized.

Any suitable electric lock may be used, but I prefer to use one of the type disclosed in the copending application for Letters Patent of the United States of Herbert L. Bone, Serial No. 67,392, filed December 27, 1948, entitled Railway Traffic Controlling Apparatus.

A lever lock rod 42, of conventional construction, is attached to the center throw lever 36, and cooperates with the pedal 41 to prevent its return to its normal latching position when the hand-throw lever 36 has been moved out of the jaw of the latch. A bolt 43 is provided, which in the position shown has one end projecting under the pedal 41 so as to prevent its downward movement in the latch releasing direction. This bolt 43 moves in a guide 44 attached to the mounting plate 38, and its opposite end is pivotally connected to a link 45 whose opposite end is in turn connected to an eccentric pin on the hand-throw lever 46 of the circuit controller 37.

When the parts are in the position shown in the drawing, and it is desired to use the crossover track, then the switchman must first operate the circuit controller by moving the hand-throw lever 46 from the position shown through 180 degrees to its reverse position. During this movement, the heavy duty contacts of the circuit controller shunt the track circuit so that the signals on the main line track are set at stop. At the same time the end of bolt 43 moves out from under pedal 41. The light duty contact of the circuit controller 37 initiates the operation of a timing relay which, at the end of a predetermined period of time, energizes the electric lock 39, so that thereafter depression of the pedal 41 releases latch 40 and allows operation of the center throw lever 36 to release the locks on the track switches. The switches may then be reversed by means of their levers 1V and 2V.

After the train has passed over the crossover, it may be restored to its previous condition by throwing the two switches to their normal positions, restoring their locks by returning the center throw lever 36 to its normal position, locking that lever by returning the pedal 41 to its normal position, and then operating the hand-throw lever 46 of the circuit controller 37 to its normal position.

It should be noted that the pedal 41, when depressed, blocks the return movement of the bolt 43 and thereby prevents restoration of the circuit controller lever 46 to its normal position before the pedal 41 has been restored to its normal position.

A pair of brackets 47 are attached to the plate 38 so as to receive the lever 46 in its normal and reverse positions. The brackets 47 are provided with suitable openings for the application of padlocks or other devices to prevent op-

eration by unauthorized persons and to hold the lever down during passage of a train over the controller.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus, comprising a track switch, a signal governing traffic movements over said switch, a lever movable between normal and reverse positions for controlling said track switch; an electric lock for holding said lever in its normal position including a latch, a pedal for operating the latch having a normal latching position and movable therefrom to a latch releasing position, a lock dog biased to a locking position in which it prevents operation of the pedal to release the latch, and an electromagnet for moving the lock dog from its locking position to a lock releasing position; an electric circuit controller having contacts for controlling said electromagnet and said signal, a hand-throw lever for said controller movable between a normal position in which the electromagnet is deenergized and the signal controlling contacts permit clearing of the signal and a reverse position in which the electromagnet may be energized and the signal is set to stop approaching traffic, an abutment movable concurrently with said pedal, a bolt connected to said circuit controller lever for concurrent movement therewith, said bolt being moved between a blocking position and an unblocking position as said controller lever is moved between its normal and reverse positions, respectively, said bolt being effective in its blocking position to block the abutment and prevent movement of the pedal from its normal latching position and in its unblocking position to permit movement of the pedal to its latch releasing position, and means operated by movement of the switch controlling lever away from its normal position to hold the pedal in its latch releasing position, said abutment being effective when the pedal is in its latch releasing position to block a return movement of the bolt to its block position, so that the switch controlling lever must be restored to its normal position and the pedal must be restored to its latching position before the controller lever can be restored to its normal position.

2. Railway traffic controlling apparatus, comprising a track switch, a signal governing traffic movements over said switch, a lever movable between normal and reverse positions for controlling said track switch; a lock for holding said lever in its normal position including a latch, a pedal for operating the latch having a normal latching position and movable therefrom to a latch releasing position, a lock dog biased to a locking position in which it prevents operation of the pedal to release the latch, and means for moving the lock dog from its locking position to a lock releasing position including time controlled means for introducing a time delay between initiation of the operation thereof and the movement of the lock dog to its lock releasing position; an electric circuit controller having contacts for controlling said

signal, means associated with the circuit controller for initiating the operation of said time controlled means, manual operating means for said controller movable between a normal position in which the operation of the time controlled means is not initiated and the signal controlling contacts permit clearing of the signal and a reverse position in which operation of the time controlled means is initiated and the signal is set to stop approaching traffic; an abutment movable concurrently with said pedal, and a bolt connected to said circuit controller lever for concurrent movement therewith, said bolt being moved between a blocking position and an unblocking position as said controller lever moves between its normal and reverse positions, respectively, said bolt being effective in its blocking position to block the abutment and prevent movement of the pedal from its normal latching position and in its unblocking position to permit movement of the pedal to its latch releasing position, and means operated by movement of the switch controlling lever away from its normal position to hold the pedal in its latch releasing position, said abutment being effective when the pedal is in its latch releasing position to block a return movement of the bolt to its blocking position, so that the switch controlling lever must be restored to its normal position and the pedal must be restored to its latching position before the controller lever can be restored to its normal position.

3. Railway traffic controlling apparatus, comprising a track switch, a signal governing traffic movements over said switch, a lever mounted between the track rails adjacent the switch and movable between normal and reverse positions for controlling the switch; an electric lock mounted between the track rails for holding said lever in its normal position including a latch, a pedal for operating the latch having a normal latching position and movable in a vertical plane to a latch releasing position, a lock dog biased to a locking position in which it prevents operation of the pedal to release the latch, and an electromagnet for moving the lock dog from its locking position to a lock releasing position; an electric circuit controller having contacts for controlling said winding and said signal, a hand-throw lever mounted between the rails and connected to said controller and movable between a normal position in which the electromagnet is deenergized and the signal controlling contacts permit clearing of the signal and a reverse position in which the electromagnet may be energized and the signal is set to stop approaching traffic, an abutment movable vertically concurrently with said pedal, and a bolt connected to said circuit controller lever for concurrent movement therewith along a horizontal path, means supporting said bolt so that it lies in the path of said abutment when the controller lever is in its normal position and prevents operation of the pedal, said bolt being moved out of the path of said abutment upon movement of the controller lever to its reverse position, said abutment being effective upon a subsequent lever releasing movement of the pedal to block a return movement of the bolt so that said pedal must be restored to its normal position before the controller lever can be restored to its normal position.

4. Apparatus for controlling the movement of traffic over an electric railway in which the track rails are employed as conductors of pro-

pulsion current, comprising a track switch, a signal governing traffic movements over said switch, signal control means including a track relay connected across said track rails, said signal control means being effective when said track relay is deenergized by the shunting of the rails to set said signal to stop, a lever movable between normal and reverse positions for controlling said track switch; an electric lock for holding said lever in its normal position including a latch, a pedal for operating the latch having a normal latching position and movable therefrom to a latch releasing position, a lock dog biased to a locking position in which it prevents operation of the pedal to release the latch, and an electric winding for moving the lock dog from its locking position to a lock releasing position; an electric circuit for energizing said winding, an electric circuit controller having light duty contacts for controlling said winding circuit and heavy duty contacts for shunting said track rails, a hand-throw lever for said controller movable between a normal position in which the winding is deenergized and the track rails are not shunted by the heavy duty contacts and a reverse position in which the winding may be energized and the track rails are shunted by the heavy duty contacts, an abutment movable concurrently with said pedal, and a bolt connected to said circuit controller lever for concurrent movement therewith, said bolt being moved between a blocking position and an unblocking position as said controller lever moves between its normal and reverse positions, respectively, said bolt being effective in its blocking position to block the abutment and prevent movement of the pedal from its normal latching position in its unblocking position to permit movement of the pedal to its latch releasing position, said abutment being effective when the pedal is in its latch releasing position to block a return movement of the bolt to its blocking position, so that the pedal must be restored to its normal latching position before the controller lever can be restored to its normal position.

5. Railway traffic controlling apparatus, comprising a track switch, a signal governing traffic movements over said switch, a lever movable between normal and reverse positions for controlling said track switch; an electric lock for holding said lever in its normal position including a latch, a pedal for operating the latch having a normal latching position and movable downwardly therefrom to a latch releasing position, a lock dog biased to a locking position in which it prevents operation of the pedal to release the latch, and an electric winding for moving the lock dog from its locking position to a lock releasing position; an electric circuit controller having contacts for controlling said winding and said signal, a hand-throw lever for said controller movable between a normal position in which the winding is deenergized and the signal controlling contacts permit clearing of the signal and a reverse position in which the winding may be energized and the signal is set to stop approaching traffic, an abutment movable concurrently with said pedal, a bolt, a link connecting one end of said bolt to said circuit controller lever for concurrent movement therewith, and means supporting said bolt and guiding it for movement along a horizontal path, said bolt having its opposite end in the path of said abutment when the controller lever is in its normal position to prevent a latch

11

releasing operation of the pedal, said bolt being moved out of the path of said abutment upon movement of the controller lever to its reverse position, said abutment being effective upon a subsequent lever releasing movement of the pedal to block a return movement of the bolt so that said pedal must be restored to its normal position before the controller lever can be restored to its normal position.

6. Railway traffic controlling apparatus adapted for mounting between the rails of a railway track to interlock a circuit controller hand-throw lever with a switch lock pedal, comprising an abutment movable concurrently with said pedal, a bolt, a link connecting one end of the bolt to the lever for concurrent movement therewith, and means supporting said bolt and guiding it for movement along a horizontal path, said bolt having its opposite end in the path of said abutment when the lever is in its normal position to prevent operation of the pedal, said bolt being moved out of the path of the abutment upon movement of the lever to its reverse position, said abutment being effective upon a subsequent operation of the pedal to block a return movement of the bolt and lever to their normal positions.

7. Railway traffic controlling apparatus adapted for mounting between the rails of a railway track, a comprising a switch lock having a pedal movable in a generally vertical direction, a controller hand-throw lever movable between normal and reverse horizontal positions, an abutment movable concurrently with the pedal, a bolt, a link connecting one end of the bolt to the lever, and means supporting the bolt and guiding it for movement along a horizontal path, said bolt having its opposite end in the path of said abutment when the lever is in its normal position to prevent operation of the pedal, said bolt being moved out of the path of the abutment upon movement of the lever to its reverse position, said abutment being effective upon a subsequent operation of the pedal to block a return movement of the bolt and lever to their normal positions.

8. Apparatus for enforcing a predetermined sequence of movement between first and second members, each movable between normal and reverse positions, comprising a rotatable abutment

movable concurrently with said first member and having normal and reverse positions corresponding to the normal and reverse positions of said first member, a bolt movable concurrently with said second member along a path intersecting the path of said abutment and having normal and reverse positions corresponding to the normal and reverse positions of said second member, said bolt being effective in its normal position to block the path of the abutment and thereby prevent movement of the first member away from its normal position, said bolt being effective when said second member is moved to its normal position to move out of the path of the abutment and permit movement of the first member to its reverse position, said abutment being effective when the first member is away from its normal position to block the return movement of the bolt and hence to prevent restoration of the second member to its normal position.

9. Apparatus for enforcing a predetermined sequence of movement between first and second members, each movable between normal and reverse positions, comprising an apertured rotatable disc connected to said first member for concurrent movement therewith, a longitudinally movable bolt connected to said second member for concurrent movement therewith, said bolt being received in the aperture in said disc when both members are in their normal positions, so that the second member must be moved away from its normal position before the first member can be so moved, said disc being effective upon movement of the first member away from its normal position to block a restoring movement of the bolt, so that the first member must be returned to its normal position before the second member can be returned to its normal position.
